 Mass., a corporation of Delaware

Application May 27, 1946, Serial No. 672,468

2 Claims. (Cl. 321—40)

1

This invention relates to rectifying systems for multi-phase, alternating-current power supplies, and more particularly to rectifying systems of the general character indicated which include grid-controlled, gaseous-discharge tubes, commonly known as thyratrons.

An object of the present invention is to provide such rectifying systems with simple and efficient means for obtaining a continuously variable output voltage.

Another object of the present invention is to provide such rectifying systems with means for protecting the same against possible damage by the inverse voltages of the power supply.

These and other objects of the present invention, which will become more apparent as the detailed description thereof progresses, are attained, briefly, in the following manner:

The system contemplates the provision of a plurality of gaseous-discharge tubes each of which includes a cathode, an anode, and a control grid, said tubes having their anode-cathode and grid-cathode circuits so connected, in phase opposition, to a multi-phase, alternating-current power supply to be rectified as to be initially non-conducting. A load impedance is connected in series with the potential difference applied between the anodes and cathodes of said gaseous-discharge tubes, and means are provided for shifting the initial phase of the potential difference applied between the control grids and cathodes of said tubes, whereby said tubes become successively conducting, each for a time interval, the duration of which is a function of the magnitude of said phase shift. The conducting state of each of said gaseous-discharge tubes causes a current to flow through said load impedance, and the average potential developed across said load impedance is a function of the duration of said time interval. Thus, by adjusting the magnitude of said phase shift, the magnitude of the output voltage can be controlled between zero and the maximum of which the system is capable.

The system also contemplates the provision of a second group of gaseous-discharge tubes, each of which includes a cathode and an anode, this second group of tubes being connected, respectively, in series with the tubes of the first above-mentioned group. The arrangement is such that the anodes of said first-named gaseous-discharge tubes can never go so negative with respect to their corresponding cathodes as to subject said tubes to damaging inverse voltages.

In the accompanying specification there shall be described, and in the annexed drawings shown,

2

an illustrative embodiment of the rectifying system of the present invention. It is, however, to be clearly understood that the present invention is not to be limited to the details herein shown and described for purposes of illustration only, inasmuch as changes therein may be made without the exercise of invention, and within the true spirit and scope of the claims hereto appended.

In said drawing, Fig. 1 is a circuit diagram of 10 a rectifying system assembled in accordance with the principles of the present invention; and

Fig. 2 shows the relationships between the various voltages applied to the system from the power supply.

15 Referring now more in detail to the aforesaid illustrative embodiment of the present invention, with particular reference to Fig. 1 of the drawing, the numerals 10, 11 and 12 generally designate gaseous-discharge tubes, known as thyratrons, 20 and including, respectively, cathodes 13, 14 and 15, anodes 16, 17 and 18, and control grids 19, 20 and 21.

The anodes 16, 17 and 18 of said tubes 10, 11 and 12 are connected, respectively, to the outer 25 terminals of secondary windings 22, 23 and 24 of a multi-phase power transformer 25, the inner terminals of said windings being connected together and constituting a neutral reference point 26.

30 Said transformer 25 additionally includes primary windings 27, 28 and 29 connected to lines 30, 31 and 32 of a three-phase, alternating-current, commercial power source, and another group of secondary windings 33, 34 and 35 connected together at their inner terminals, as at a neutral reference point 36, said first and second-named secondary windings being so disposed with respect to each other that the voltages developed thereacross are in phase opposition.

35 40 The anodes 16, 17 and 18 of the tubes 10, 11 and 12 are also connected, respectively, to cathodes 37, 38 and 39 of additional gaseous-discharge tubes 40, 41 and 42, said last-named tubes including anodes 43, 44 and 45 connected to ground, 45 as at 46, and, through a load resistor 47, by-passed by a capacitor 48, to the cathodes 13, 14 and 15 of said first-named gaseous-discharge tubes.

Said cathodes 13, 14 and 15 of said tubes 10, 50 11 and 12 are also connected, through a bias resistor 49, by-passed by a capacitor 50, to the neutral point 36 of the second above-mentioned secondary windings 33, 34 and 35, and, through contacts 51 and 52 of a ganged switch 53, and a resistor 54 and relay 55, to ground, as at 56. The

relay 55 controls contacts in the lines 30, 31 and 32.

The outer terminals of the secondary windings 33, 34 and 35 are connected, respectively, through resistors 57, 58 and 59, to one of the end terminals 60, 61 and 62 of potentiometers 63, 64 and 65, the remaining end terminals 66, 67 and 68 of said potentiometers being connected respectively, through resistors 69, 70 and 71, to the outer terminals of the secondary windings 34, 35 and 33. 10 The resistance between the end terminals of each of the potentiometers 63, 64 and 65 is center-tapped, respectively, as at 72, 73 and 74, whereby said potentiometers comprise, respectively, pairs of resistors 75 and 76, 77 and 78, and 79 and 80. The center taps 72, 73 and 74 are connected, respectively, to the outer terminals of the secondary windings 35, 33 and 34.

By means of the potentiometer connections just described, two phases of the power supply are applied to each potentiometer, and, as will hereinafter be further described, phase shifts of up to substantially 240° may be obtained.

The potentiometers 63, 64 and 65 include, respectively, adjustable arms 81, 82 and 83 which are ganged together, as indicated by the broken lines, and said adjustable arms are connected, respectively, through pairs of series-connected resistors 84 and 85, 86 and 87, and 88 and 89, to the control grids 19, 20 and 21 of the gaseous-discharge tubes 10, 11 and 12. The junctions between the pairs of series-connected resistors just described are connected, respectively, to contacts 90, 91 and 92 included in the switch 53. Additional contacts 93, 94 and 95, cooperable, respectively, with the contacts 90, 91 and 92, are connected, respectively, to the end terminals 60, 61 and 62 of the potentiometers 63, 64 and 65.

The grids 19, 20 and 21 of the tubes 10, 11 and 12 are also connected, respectively, through capacitors 96, 97 and 98, to the cathodes 13, 14 and 15 of said tubes.

This completes the description of the aforesaid illustrative embodiment of the invention and the mode of operation thereof will now be described, for which purpose reference is made to Fig. 2 of the drawing as well as to Fig. 1.

In said Fig. 2 of the drawing, there are shown three main voltages A, B, and C corresponding to the three phases, spaced 120° apart, of the commercial power lines 30, 31 and 32, and three commutating voltages A', B' and C', likewise spaced 120° apart, but in phase opposition, respectively, to said voltages A, B and C.

It will be assumed, for the purposes of this specification, that the main voltages A, B and C, which appear across the secondary windings 22, 23 and 24, have a peak value of about 5,000 volts, and that the commutating voltages A', B' and C', which appear across the secondary windings 33, 34 and 35, have a peak value of about 150 volts.

Consider the time t_1 , at which the main voltage A is somewhat greater than one-half its positive peak, for example, 2,550 volts; the main voltage B is somewhat less than its negative peak, for example, 4,950 volts; and the main voltage C is somewhat less than one-half its positive peak, for example, 2,450 volts, all with respect to the neutral reference point 26. At the same time, the commutating voltage A' is somewhat greater than one-half its negative peak, for example, 130 volts; the commutating voltage B' is somewhat less than its positive peak, for example, 145 volts; and the commutating voltage C' is somewhat less

than one-half its negative peak, for example, 120 volts, all with respect to the neutral reference point 36.

Under these circumstances, the cathode 37 of the gaseous-discharge tube 40 will be positive with respect to the anode 43 of said tube, and said tube will be non-conducting. The cathode 39 of the gaseous-discharge tube 42 will be positive with respect to the anode 45 of said tube, and said tube will also be non-conducting. However, the cathode 38 of the gaseous-discharge tube 41 will be negative with respect to the anode 44 of said tube, and said tube will be conducting.

Hence, there appears upon the anode 16 of the gaseous-discharge tube 10 a voltage which is 7,500 volts positive (the sum of voltages across the windings 22 and 23) with respect to the cathode 13 of said tube, and the latter, if it were not for the fact that the instantaneous voltage on its control grid 19 was 130 volts negative with respect to its cathode 13, would be conducting.

There appears upon the anode 18 of the gaseous-discharge tube 12 a voltage which is 7,400 volts positive (the sum of the voltages across the windings 23 and 24) with respect to the cathode 15 of said tube, but the control grid 21 of the latter is 120 volts negative with respect to the cathode 15, and therefore, said tube, too, is non-conducting.

30 The anode 17 of the gaseous-discharge tube 11 is, by reason of the conducting gaseous-discharge tube 41, at the same potential as the cathode 14 of said first-named tube, and therefore, the latter is non-conducting, even though its control grid 20 is 145 volts positive with respect to its cathode 14.

Thus, at the time t_1 , none of the gaseous-discharge tubes 10, 11 and 12 is conducting, and consideration of the voltage relationships at any time within the 360° illustrated in Fig. 2 of the drawing will reveal the same non-conducting conditions, these conditions obtaining as long as the commutating voltages A', B' and C' are maintained 180° out of phase with the main voltages A, B and C.

35 The potentiometers 63, 64 and 65, and the various resistors between said potentiometers and the gaseous-discharge tubes 10, 11 and 12 and the secondary windings 33, 34 and 35, preferably, are of such values that when the adjustable arms 81, 82 and 83 of said potentiometers are in their extreme counter-clockwise positions, the out-of-phase relationships above referred to exists.

Now, assume that the adjustable arms 81, 82 and 83 of the potentiometers 63, 64 and 65 are moved, in a clockwise direction, to advance the phase of the commutating voltages, each, 90° . Further assume that the commutating voltages are now represented by the sine waves A'', B'' and C'' in Fig. 2 of the drawing, and consider the time t_2 .

At said time t_2 , the main voltage A is at its positive peak, 5,000 volts; and the main voltages B and C are each at one-half their negative peak, 2,500 volts, the former becoming less negative, and the latter becoming more negative. At the same instant, the commutating voltage A'' is zero, but starting on its positive alternation; the commutating voltage B'' is somewhat less than its negative peak, for example, 145 volts; and the commutating voltage C'' is somewhat less than its positive peak, for example, 145 volts.

Under these circumstances, the cathode 37 of the gaseous-discharge tube 40 is positive with respect to the anode 43 of said tube, and said

tube will be non-conducting. The cathode 38 of the gaseous-discharge tube 41 will, until the point of the cross-over between the main voltages B and C is reached, be negative with respect to the anode 44 of said tube, and until said cross-over point is reached, said tube will be conducting. As soon as said cross-over point is passed, the cathode 39 of the tube 41 will be positive with respect to the anode 44 of said tube, and said tube will no longer conduct. The cathode 39 of the gaseous-discharge tube 42 will, until the above-referred to cross-over point is reached, be positive with respect to the anode 45 of said tube, and until said cross-over point is reached, said tube will be non-conducting. As soon as said cross-over point is passed, the cathode 39 of the tube 42 will be negative with respect to the anode 45 of said tube, and said tube will begin to conduct.

Hence, there appears upon the anode 16 of the gaseous-discharge tube 10 a voltage which is 7,500 volts positive (the sum of the voltages across the windings 22 and 24) with respect to the cathode 13 of said tube, and inasmuch as the commutating voltage A' is, at the instant under consideration, going positive, said tube 10 will begin to conduct.

Now, during the periods that no one of the tubes 10, 11 and 12 is conducting, the potential of the cathodes 13, 14 and 15 of said tubes follows the lower envelope of the voltages A, B and C, but as soon as any one of said tubes becomes conducting, said cathodes attain a potential equal to the potential of the anode of the instantaneously conducting tube minus the small drop within said conducting tube itself.

Therefore, as soon as the tube 10 becomes conducting as aforesaid, there appears upon the anode 17 of the gaseous-discharge tube 11 a voltage which is somewhat less than 7,504 volts negative with respect to the cathode 14 of said tube 11, and said tube will not conduct. Actually, the control grid 29 of said tube 11 is, at this instant, about 145 volts negative with respect to the cathode 11 thereof.

There appears upon the anode 18 of the gaseous-discharge tube 12 a voltage which is, at the instant under consideration, somewhat more than 7,500 volts negative with respect to the cathode 15 of said tube, and therefore, even though the control grid 21 of said tube is about 145 volts positive with respect to said cathode 15, said tube 12 will not conduct.

Now, once the tube 10 is conducting, it will continue to conduct until its anode potential goes negative with respect to its cathode. This would not occur until time t_3 were reached if it were not for the capacitor 48. The residual voltage across said capacitor 48 causes this to occur, actually, at some short time before the time t_3 .

At that time, the anode and control grid voltages of the gaseous-discharge tube 11 will be the same as the anode and control grid voltages of the gaseous-discharge tube 10 were at the time t_2 . Therefore, the tube 11 will start to conduct, the cathodes 13, 14 and 15 will jump almost to the potential of the anode 17 of said tube 11, and inasmuch as this potential is positive with respect to the anode 16 of the tube 10, the latter will cease conducting.

The same sort of commutation will occur shortly before time t_4 , when the gaseous-discharge tube 12 will start to conduct and the gaseous-discharge tube 11 will stop conducting.

As each tube 10, 11 and 12 conducts, current

will flow through the load resistor 47, said current producing the output voltage of the system.

With a phase shift of 90° , such as has been under consideration in the foregoing description, the tubes 10, 11 and 12 will conduct for the periods indicated by the shaded portions, respectively, from left to right, superimposed on the sine waves A, B and C. As indicated in earlier portions of this specification, the magnitude of the phase shift introduced by adjustment of the ganged potentiometer arms 81, 82 and 83 will control the duration of the conducting intervals of the tubes 10, 11 and 12, and, in turn, the duration of said time intervals will control the average output voltage developed across the load resistor 48.

The ganged switch 53 enables the output voltage to be tuned on and off without regard to the magnitude thereof, and the relay 55 is utilized to automatically open the power lines in the event said switch 53, when closed, fails to reduce the output voltage substantially to zero.

This completes the description of the mode of operation of the aforesaid illustrative embodiment of the present invention.

It will be noted from all of the foregoing that the present invention provides a rectifying system for a multi-phase, alternating-current power supply, especially, a rectifying system which includes thyratrons, in which there is incorporated a simple and efficient means for obtaining continuously variable output voltage. It will further be noted that the rectifying system of the present invention is so designed as to prevent the same from being damaged by excessive inverse voltages of the power supply.

Other objects and advantages of the present invention will readily occur to those skilled in the art to which the same relates.

What is claimed is:

40. 1. A rectifying system for a multi-phase, alternating-current power supply comprising: a plurality of gaseous-discharge tubes each of which includes a cathode, an anode, and a control grid; a plurality of additional gaseous-discharge tubes each of which includes a cathode and an anode; said first and second-named gaseous-discharge tubes being connected, respectively, in series with each other; means adapted to be energized from said power supply, for applying such potential differences between the anodes and cathodes, and the control grids and cathodes of said first-named gaseous-discharge tubes, and between the anodes and cathodes of said second-named gaseous-discharge tubes as to maintain said first-named tubes initially non-conducting; a load impedance connected across said series-connected, first and second-named gaseous-discharge tubes; resistance networks connected in series with the potential difference applied between the control grids and cathodes of said first-named gaseous-discharge tubes, for so shifting the phase of said potential difference as to render said gaseous-discharge tubes successively conducting, each for a time interval which is a function of the magnitude of said phase shift; and means across which control-grid rectification develops a bias sufficient to maintain all but one of said first-named gaseous-discharge tubes non-conducting; the current flowing as a result of the conducting state of each of said first-named gaseous-discharge tubes developing an average potential across said load impedance the magnitude of which is a function of the duration of said time interval.
45. 2. A rectifying system for a multi-phase, alternating-current power supply comprising: a plu-

rality of gaseous-discharge tubes each of which includes a cathode, an anode, and a control grid; a plurality of additional gaseous-discharge tubes each of which includes a cathode and an anode; said first and second-named gaseous-discharge tubes being connected, respectively, in series with each other; means, adapted to be energized from said power supply, for applying such potential differences between the anodes and cathodes, and the control grids and cathodes of said first-named gaseous-discharge tubes, and between the anodes and cathodes of said second-named gaseous-discharge tubes as to maintain said first-named tubes initially non-conducting; a load impedance connected across said series-connected, 15 first and second-named gaseous-discharge tubes; resistance networks connected in series with the potential difference applied between the control grids and cathodes of said first-named gaseous-discharge tubes, for so shifting the phase of said 20 potential difference as to render said gaseous-discharge tubes successively conducting, each for a time interval which is a function of the magnitude of said phase shift; and a resistance 25 capacitance network across which control-grid

10

5

rectification develops a bias sufficient to maintain all but one of said first-named gaseous-discharge tubes non-conducting; the current flowing as a result of the conducting state of each of said first-named gaseous-discharge tubes developing an average potential across said load impedance the magnitude of which is a function of the duration of said time interval.
